(57) **CLAIM**

The ornamental design for the automated coffee vending kiosk, as shown and described.

DESCRIPTION

FIG. 1 is an isometric view of an automated coffee vending kiosk showing our design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

In the drawings, the broken lines represent portions of the automated coffee vending kiosk and form no part of the claimed design.

1 Claim, 6 Drawing Sheets
